Property Agency; Daniel Boudwin

(57) **CLAIM**

The ornamental design for a pipe stake, as shown and described.

DESCRIPTION

FIG. 1 shows a perspective view of a pipe stake;
FIG. 2 shows a front view of the pipe stake;
FIG. 3 shows a rear view of the pipe stake;
FIG. 4 shows a right side view of the pipe stake;
FIG. 5 shows a left side view of the pipe stake;
FIG. 6 shows a top plan view of the pipe stake; and,
FIG. 7 shows a bottom plan view of the pipe stake.
The shade lines in the Figures show contour and not surface
ornamentation.

1 Claim, 4 Drawing Sheets
